UNITED STATES PATENT OFFICE.

WALTER HEILEMANN AND HEINRICH KANONENBERG, OF ESSEN-ON-THE-RUHE, GERMANY, ASSIGNORS TO FRIED. KRUPP AKTIENGESELLSCHAFT, OF ESSEN-ON-THE-RUHR, GERMANY.

PIVOT-STAND FOR MOBILE ARTILLERY.

1,098,258.

Specification of Letters Patent.

Patented May 26, 1914.

Application filed July 14, 1913. Serial No. 778,981.

To all whom it may concern:

Be it known that we, WALTER HEILEMANN and HEINRICH KANONENBERG, residing at Essen-on-the-Ruhr, Germany, both subjects 5 of the Emperor of Germany, have invented a certain new and useful Improvement in Pivot-Stands for Mobile Artillery, of which the following is a specification.

The present invention relates to pivot 10 stands for mobile artillery which are arranged in such a manner that the gun carriage proper may be easily and quickly swung when a deep groove or trench is provided for the trail end of the gun carriage, 15 for the purpose of giving to the gun carriage a higher elevation than that for which the carriage has been constructed.

In the accompanying drawing one embodiment of the invention has been illustrated; and Figure 1 shows a side view partly 20 in section of a gun on a pivot stand; Fig. 2 a similar view to Fig. 1, but with different relative position of the details; and Fig. 3 a detail in section and in larger scale.

25 The pivot stand has a base A, and a top portion consisting of two parts, namely a pivot B and a top carriage B¹, the former being provided with a trunnion b² around the axis of which the top portion B, B¹ is 30 mounted to be turned relative to the base A. The top carriage B¹ is provided with bearings b³ and b⁴ for the axle-tree G of the gun carriage, and is mounted on the pivot B in such a manner that it may be displaced in 35 the longitudinal direction of the gun carriage when the latter rests on the pivot stand. To connect the pivot stand with the gun carriage is provided a ring R mounted in a groove a⁵ on the base A, and a fork-shaped rod E hinged to journals r¹ of this ring, which rod connects with the trail body F of the gun carriage by means of an eyelet e¹ and a hook f¹.

40 On an upward projection r² of the ring R is hinged an accumulator M, M¹, N, see particularly Fig. 3. This accumulator consists of two sleeves M, M¹ relatively 45 slidable to each other, and a spring N abutting against both of these sleeves. The inner sleeve M is hinged to the projection r² of the ring R by means of a bolt r³, the axis of which is parallel to the axis of the journals r¹. The outer sleeve M¹ carries a ball joint m² which is intended to connect with

a socket f² provided on the underside of the 55 trail body F, see Fig. 3.

As will be evident from the drawing the gun carriage consists of the usual parts found in mobile artillery; its trail end rests on level ground with the normal trail pressure.

On drawing the gun carriage on to the pivot stand, the trail end is raised by means of the hand spike K, and the accumulator M, M¹, N swung from the transportation 60 position, indicated by dot and dash lines, Fig. 1, into the position in which the ball joint m² may enter into engagement with the socket f² of the trail body. If now the trail end is laid down on the ground this engagement will take place, and the sleeve M¹ will thereupon slide down on the sleeve M compressing the spring N.

When the gun carriage is to be swung around, the trail end has to be raised. A 75 displacement of the top carriage B¹ of the pivot stand relative to the pivot B will then take place, so that the pivot stand need not be tilted. The spring N expands simultaneously, whereby the swinging of the gun carriage will be facilitated. In the turning movement of the gun carriage, the upper 80 part B¹, the ring R, the rod E and the accumulator M, M¹, N of the pivot stand partake.

85 The above related action of the accumulator is particularly advantageous when the trail end is laid down into a groove or trench in the ground for the purpose of giving a greater elevation to the gun carriage 90 than that for which the carriage is constructed. The center of gravity of the gun carriage will then take such a position relative to the axle-tree G that the trail end will rest with considerably greater pressure 95 on the ground than in the position illustrated in Fig. 1.

We claim:

1. A pivot stand for mobile artillery having a trail, comprising a base and a top portion mounted to revolve on said base, said top portion being constructed to engage with and support the forward end of the gun carriage; and an accumulator between the base of the pivot stand and the trail of the gun carriage, said accumulator being adapted to be strained by the weight of the trail end.

2. A pivot stand for mobile artillery having a top carriage and a base, said top carriage being constructed to engage with and support the forward end of the gun carriage, and being displaceable relatively to said base in the longitudinal direction of the gun carriage; resilient means between the trail of the gun carriage and said base, and a hinged connection between the trail and said base, whereby said top carriage will be horizontally displaced relative to said base a distance corresponding to the position of the trail end relatively to the ground when moved in a vertical direction.
3. A pivot stand for mobile artillery having a top carriage and a base, said top carriage being constructed to engage with and support the forward end of the gun carriage and being displaceable relatively to said base in the longitudinal direction of the gun carriage, a resilient member on said base for partially sustaining the weight of the gun carriage, and a hinged connection between the trail and said base, said hinged connection comprising a ring revoluble around said base, a pair of horizontal trunnions on said ring and a fork mounted to oscillate on said trunnions connecting them with said trail; whereby said top carriage will be displaced horizontally relative to said base a distance corresponding to the

position of the trail end relative to the ground when moved in a vertical direction.

4. A pivot stand for mobile artillery having a top carriage and a base, said top carriage forming bearings for the axle of the gun carriage and being displaceable relatively to said base in the longitudinal direction of the gun carriage, and a hinged connection between the trail and said base, said hinged connection comprising a ring revoluble around said base, a pair of horizontal trunnions on said ring and a fork mounted to oscillate on said trunnions connecting them with said trail; a projection on said ring, a power brake hinged to said projection, a ball and socket bearing between said brake and said trail, said brake being compressed by the weight of the trail end; whereby said top carriage will be horizontally displaced relative to said base a distance corresponding to the position of the trail end relative to the ground when moved in a vertical direction.

The foregoing specification signed at Bar-
men, Germany, this 23rd day of June, 1913.
